UNITED STATES PATENT OFFICE

2,477,151

SHOELACE

Herbert J. Stapleton, Kalamazoo, Mich., assignor
of one-half to Viola D. Stapleton, Kalamazoo,
Mich.

Application June 3, 1944, Serial No. 538,598

5 Claims. (Cl. 24—143)

1

This invention relates to improvements in shoe laces.

The main objects of this invention are:

First, to provide a shoe lace which may be easily tied and at the same time does not become untied if the knot is formed with reasonable care.

Second, to provide a shoe lace which does not slip when tied and which may be tied in the usual manner.

Third, to provide a shoe lace embodying these advantages which is attractive and distinctive in appearance and capable of withstanding relatively heavy stresses.

Objects pertaining to details and economies of the invention will definitely appear from the description to follow. The invention is defined in the claims.

It is a matter of common experience that shoe laces of standard types are likely to become untied, even when great care is exercised in tying the same. This is particularly true with laces of children's shoes; much time is spent in retying and falls frequently result from a shoe lace becoming untied. Shoe laces embodying this invention are unlikely to become untied if fairly reasonable care is taken in tying the same or if the knot is drawn up reasonably tight. I am aware that attempts have been made to provide laces intended to remain tied, but so far as I am aware the results aimed at have not been effectively attained and the laces are unattractive in appearance.

In the accompanying drawing the figure is a fragmentary view of a shoe lace embodying my invention, partially in side elevation, partially in edge elevation and partially in longitudinal section, certain portions being shown conventionally.

The embodiment of my invention illustrated in the accompanying drawing comprises a braided flat tape-like body member 1 of substantial width and of relatively soft and yielding textile material. This may be of the well-known braided tubular form. The lace tips 2 which are preferably duplicates, are formed of metal retainingly clamped upon the ends of the body portion. With this body portion I associate a strand 3, preferably braided textile of round section and relatively unyielding, that is, unyielding as compared to the body portion. This strand 3 is roved or woven back and forth through the body portion at spaced intervals 4, providing alternately disposed reaches 5 on the sides of the body portion constituting raised ribs. This strand is preferably located centrally as illustrated, the

reaches 5 being of substantial length, thereby providing a longitudinal series of raised ribs and spaces 6 between the ribs. The ends of the strand are clampingly retained or secured by means of the lace tips 2, the ends being secured with the reaches of the strand drawn tight against the sides of the body portion. The length of the reaches may be very considerably varied but preferably they are of substantial length or substantially spaced so that the body portion of the lace may be drawn into the spaces between the raised rib portions when the knot is formed, thereby effectively preventing slipping.

The strand is preferably formed so that, inherent, it is less yieldable than the body portion of the lace, that is, it is more firmly or tightly braided than the body portion of the lace, and I also preferably impregnate the strand with some material which tends to stiffen the same or render it less yielding. This material is preferably of a character which substantially increases the frictional quality or resistance of the strand. Certain latex and resin preparations or compositions may be used for this purpose with satisfactory results.

While the strand 3 is preferably of textile material and of round section, it may be of other section and may be formed of materials other than textiles; for example, leather or certain plastics. Laces embodying my invention are not only effective in preventing the untiring or slipping of the knot but they also minimize slipping in the lacing eyes and thus reduce strain on the knot and the tendency to loosen the knot. In addition to these advantages, the laces are attractive and distinctive in appearance. I have not attempted to illustrate or describe various embodiments or adaptations which I contemplate, as it is believed this disclosure will enable those skilled in the art to adapt or practice my invention as may be desired for the particular type or quality of lace.

Having thus described my invention what I claim as new and desire to secure by Letters Patent is:

1. A shoe lace comprising a braided flat relatively wide and relatively yieldable body member, a braided round relatively unyieldable strand woven back and forth centrally through said body member, the reaches of said strand being of substantial length and providing longitudinally spaced raised alternately disposed ribs on the sides of the body member, and tips clampingly engaging the ends of said body member and said strand with the reaches of the strand pulled

closely against the sides of the body member, said strand being of flexible textile like material throughout the length thereof to facilitate passage of the lace through the eyelets of a shoe and tying the lace into a knot, said strand as a continuous integral-like member being woven back and forth through the body member from its clamping engagement with one tip to its clamping engagement with the other tip, said ribs being bendable to conform to the bends of the tying knot of the lace and to conform to the eyelets of a shoe, said ribs constituting bendable anti-slipping means within the tying knot.

2. A shoe lace comprising a flat relatively wide body portion, a relatively narrow strand woven back and forth centrally through said body portion, the reaches of said strand constituting raised portions disposed in spaced alternating relation on the sides of the body portion, and tips retainingly engaging the ends of said body portion and said strand with the reaches of the strand pulled against the sides of the body portion, said strand as a continuous integral-like member being woven back and forth through said body portion from its retaining engagement with one tip to its retaining engagement with the other tip, said strand being of flexible textile-like material to facilitate tying the lace into a knot and passage of the same through a shoe eyelet, said raised portions being bendable to conform to the bends of the tying knot and to the eyelets of a shoe, said raised portions constituting bendable anti-slipping means within the tying knot.

3. A shoe lace comprising a relatively wide body portion, a strand roved back and forth through said body portion providing alternating raised portions on the sides of the body portion extending along the length of the body portion throughout the knot tying end portions thereof, and tips retainingly engaging the ends of said body portion and also said strand, said strand being of relatively flexible material throughout the length thereof to facilitate tying the lace into a knot and passage of the lace through shoe eyelets, said raised portions being bendable to conform to the bends in the tying knot of the lace and to conform to the eyelets of a shoe, said raised portions constituting bendable anti-slipping means within the tying knot.

4. A shoe lace comprising a relatively wide 50

body portion, and a relatively narrow strand associated with said body portion to provide longitudinally spaced raised portions on at least one side thereof extending along the length of the body portion throughout the knot tying end portions thereof, the ends of said strand being retainingly secured to said body portion, said strand being of relatively flexible material throughout the length thereof to facilitate tying the lace into a knot and passage of the lace through shoe eyelets, said raised portions being bendable to conform to the bends in the tying knot of the lace and to conform to the eyelets of a shoe, said raised portions constituting bendable anti-slipping means within the tying knot.

5. A shoe lace comprising a tape-like body portion, and a relatively narrow strand associated with said body portion to provide longitudinally spaced raised portions on at least one side thereof extending along the length of the body portion throughout the knot tying end portions thereof, said strand being impregnated to render the same substantially unyielding as compared to said body portion and to substantially add to the frictional resistance thereof, the ends of said strand being retainingly secured to said body portion, said strand being of relatively flexible material throughout the length thereof to facilitate tying the lace into a knot and passage of the lace through shoe eyelets, said raised portions being bendable to conform to the bends in the tying knot of the lace and to conform to the eyelets of a shoe, said raised portions constituting bendable anti-slipping means within the tying knot.
